US00D976948S

(12) United States Design Patent (10) Patent No.: US D976,948 S
Gehiere et al. (45) Date of Patent: * Jan. 31, 2023

(54) DISPLAY SCREEN OR PORTION THEREOF
WITH GRAPHICAL USER INTERFACE

(71) Applicant: Apple Inc., Cupertino, CA (US)

(72) Inventors: Gary William Gehiere, Santa Clara, CA (US); Amy Hung, San Francisco, CA (US); Daniel Huy Mai, Cupertino, CA (US); Jonathan Cho, San Francisco, CA (US)

(73) Assignee: Apple Inc., Cupertino, CA (US)

() Term: 15 Years

(21) Appl. No.: 29/758,325

(22) Filed: Nov. 13, 2020

Related U.S. Application Data

(63) Continuation of application No. 29/684,768, filed on Mar. 23, 2019, now Pat. No. Des. 902,235.

CLAIM

The ornamental design for a display screen or portion thereof with graphical user interface, as shown and described.

DESCRIPTION

The sole FIGURE is a front view of a display screen or portion thereof with graphical user interface showing our new design.

The peripheral dashed broken lines illustrate a display screen or portion thereof, and form no part of the claimed design.

1 Claim, 1 Drawing Sheet
